L. P. GRÁNER

ELECTRIC LIGHT EQUIPMENT

Filed June 18, 1923

Inventor:
Ladislaus Peter Gráner,
by Alexander F. Lunt
His Attorney.

UNITED STATES PATENT OFFICE.

LADISLAUS PETER GRÁNER, OF HINDHOVEN, NETHERLANDS, ASSIGNEE TO GENERAL ELECTRIC COMPANY, A CORPORATION OF NEW YORK.

ELECTRIC-LIGHT EQUIPMENT.

Application filed June 18, 1923, Serial No. 646,053, and in the Netherlands August 30, 1931.

My invention relates to improvements in electric lighting equipment in general and includes in particular alternating current light equipment in which electric lamps and condensers are used in the same circuit. In this respect my invention is in the nature of an improvement on the application of Giles Holst for United States Letters Patent, Serial No. 413,468, now Patent No. 10 1,539,572.

In equipment of the above character, the lamps used are designed for a lower voltage than the line voltage to which the equipment as a whole is applied. In using equipment of the above type, it very often happens that the filament fuses and burns out. The reason for this is as follows: The lamp is sometimes turned on when the line voltage is at a positive maximum, thereby leaving 20 the condenser in a positively charged condition. Now, if the lamp is turned on at the moment when the line voltage is at a negative maximum, a flow of current takes place through the filament, due to the combined 25 line and condenser voltages which fuses the filament.

Among the objects of my invention are, to provide means for enabling the condenser in an equipment of the above character to 30 discharge if left charged when the circuit is broken and to provide other details of improvement tending to increase the efficiency and service utility of equipment of the above character.

To accomplish the foregoing and other useful ends, my invention comprises means hereinafter more fully set forth and claimed.

The accompanying drawing is a diagrammatic representation of the lighting equipment containing the elements of my invention.

In the above drawing, the lamp filament 2 is shown tapped by three conductors 3, 4 and 5. This divides the filament into two 45 sections *a* and *b*. Associated with the conductors 4 and 5 there is a switch 7 which may be operated to close connection with either of the conductors 4 or 5. The switch 7 is shown permanently connected with one 50 of the mains 8, whereas the other main 9 is connected with the conductor 3 by way

of the switch 11. When the switch 7 is thrown over into connection with the conductor 5, the whole filament 2 is brought into circuit. In that case the current 55 passes from the conductor 8 through conductor 5 and filament 2 to the conductor 3 and back to the main 9. However, when the switch is in the position as thrown, shown in the drawing in engagement with the conductor 4, the condenser 10 is brought into circuit with the section *a* of the filament. It will be seen that under these conditions, section *a* of the filament is in series with the condenser 10 across the mains 8 and 9. If, 60 while the current is flowing through the condenser, the switch 11 is thrown open, the condenser 10 may be left charged as previously explained. If, however, the insulating medium 12 that separates the condenser 65 plates is made with a resistance such as to permit a discharge to leak through between the plates of the condenser, the charged condition will persist for only a short period. Therefore, if the switch 11 is closed again, the 70 condenser plates will be found discharged at least to such an extent as to prevent any damage occurring to the filament. It is not necessary that the insulating medium 12 be used to discharge the condensers 75 inasmuch as the condensers may be shunted by a high resistance element bridged across the terminals of the condenser, which element I have shown connected to the terminals by dotted lines. 80

Having disclosed the principle of my invention in two embodiments, other equivalent modifications will obviously suggest themselves to those versed in the art. I therefore do not wish to be limited to the 85 particular constructions shown, but rather to such embodiments which fall fairly within the scope of my claims.

What I claim as new and desire to secure by Letters Patent of the United States, is,— 90

1. In an electric lamp; an electric light filament, a condenser connected in circuit with the filament, the filament and the condenser adapted to be connected across a source of operating potential, and means 100 connecting the opposite plates of the condenser for insuring a comparatively rapid

discharge of the condenser after the lamp is disconnected from the source of operating potential.

2. In an electric lamp, an electric light filament, a condenser connected in circuit with the filament, the filament and the condenser adapted to be connected across a source of operating potential, and a high re-

sistance leak connecting the opposite plates of the condenser for insuring a comparatively rapid discharge of the condenser after the lamp is disconnected from the source of operating potential. 10

In witness whereof, I have hereunto set my hand this first day of June, 1923.

LADISLAUS PETER GRANER.

CERTIFICATE OF CORRECTION.

Patent No. 1,652,981.

Granted December 13, 1927, to

LADISLAUS PETER GRANER.

It is hereby certified that error appears in the printed specification of the above numbered patent requiring correction as follows: Page 1, line 18, for the word "on" read "off"; and that the said Letters Patent should be read with this correction therein that the same may conform to the record of the case in the Patent Office.

Signed and sealed this 31st day of January, A. D. 1928.

M. J. Moore,
Acting Commissioner of Patents.

Seal.
